UNITED STATES PATENT OFFICE.

JOHN J. ROSS, OF INTERNATIONAL FALLS, MINNESOTA.

BARKING-DRUM.

1,226,374.

Specification of Letters Patent. Patented May 29, 1917.

Application filed February 12, 1916. Serial No. 78,034.

To all whom it may concern:

Be it known that I, JOHN J. ROSS, a citizen of the United States, residing at International Falls, in the county of Koochiching and State of Minnesota, have invented a new and useful Improvement in Barking-Drums, of which the following is a specification.

This invention is designed for removing bark from wood before it is ground into wood pulp or reduced into chips for chemical pulp. In the manufacture of ground wood or chemical pulp, various kinds of soft woods are used, and this wood has to be cleaned from the bark before being ground into pulp or the finished product will contain bark making the pulp inferior and objectionable.

Heretofore bark has been removed by hand tools and by what are termed barking machines of different designs and types. Some of these devices employ revolving disks with knives, the wood being held or pressed against the disks and the disks revolved with the inserted knives under high speed, thereby cutting the bark from the wood. This process has resulted in a large waste of good material, which would otherwise be employed for making pulp. To reduce this amount of waste barking drums have been introduced, which clean the wood and remove the bark with considerable less waste than has occurred by the use of knife barkers. With this latter type of machine, the logs, blocks and sticks of wood of large diameter or size will not pass through the drums as fast as smaller ones, thus bruising and slivering the large pieces which in the manufacture of ground wood must necessarily be removed and wasted. The use of hand tools is also too laborious.

My invention is designed to overcome these objections and to separate the bark from the wood in an efficient and effective manner.

My invention therefore comprises the features of construction and combination of parts hereinafter more particularly described and claimed.

In the accompanying drawings forming part of this specification, Figure 1 is a side elevation of a portion of my improved barking mill, it being understood that the structure may be extended and made of any length desired; Fig. 2 is a section taken on the line X—X of Fig. 1; Fig. 3 is a longi-

tudinal section of a portion of a detail of my invention, and Fig. 4 is a section taken on the line Y—Y of Fig. 3.

My invention contemplates the use of a cylindrical drum or barrel preferably although not necessarily composed of sections such as A, B and C, as many sections being employed as will remove the bark and clean logs, blocks or sticks of wood preparatory of being ground or cut into wood pulp or chips for chemical pulp. Each of the sections A, B, C, etc., is of cylindrical form and of substantially even diameter, the section A being what I term the receiving section and the sections B, C, etc., the finishing sections. The total number of sections employed is dependent on the amount of wood to be barked, and the amount of tumbling action that is necessary for removing the bark.

The receiving section A has a thin cylindrical shell 2 of metal or other suitable material secured to flanged rings 3 and 4 at their opposite ends by rivets 5 or other suitable means. To these end angle rings 3 and 4 are secured such as by rivets 6, bolts or other suitable means, flat rings 7 and 8, which form bulk heads, the inner edges of which are reinforced by angle rings 9 and 10 secured thereto and forming central openings through which the logs or sticks of wood are adapted to be passed inwardly. The space between the bulk heads or ends 7 and 8 and the wall 2 forms a receptacle into which water or other soaking and washing liquid is introduced from the valved supply pipe 11 or other suitable means.

The cylindrical wall of each of the sections B and C is composed of longitudinally arranged bars 15 secured to the end rings 16 and 17 and spaced apart sufficiently to allow the bark, which is knocked off of the wood during the tumbling action in the drum, to fall through the spaces and on to a conveyer such as D of any suitable construction arranged below the drum for conducting the bark away from the machine. The sections B, C, etc., have no bulk heads, their ends being entirely open and no water or other liquid held therein.

Each of the sections A, B, C, etc. is provided with a pair of track rings such as 20 and 21 over the periphery of the casing 2 or over the cylindrically arranged bars 15 by means of rivets 22 or any other suitable means. These track rings turn in pairs of

roller bearings 23 and 24 (see Fig. 4) which are mounted upon a suitable supporting frame 25. Each of the sections A, B, C, etc. is revolved at suitable speed from a drive shaft 5 or other suitable source of power by a belt 27 engaging a sprocket wheel 28 on the section and a sprocket pinion 29 on said shaft, all of said sections being revolved in the same direction simultaneously. While 10 the drum composed of said sections is revolving the logs, blocks or other pieces of wood after being sawed to the right lengths for the usual grinders are fed or placed in the receiving drum through its outer end and by the rotation of the entire drum, the 15 pieces of wood are made to tumble over and over causing them to fall or knock against inwardly projecting bark knockers 30, which remove the bark from the wood. These bark knockers are as shown bulb angles of any 20 number desired, four being illustrated on each section, evenly distanced apart circumferentially and sloping endwise so as to form a spiral or worm, pitched to suit the conditions or time required to remove the 25 bark. The bulb angles are secured on the inner surface of each section of the drum by rivets 31 or other suitable means and preferably extend the entire length of each 30 section. The spiral bulb angles are placed in the adjacent sections of the drum behind one another endwise, so as to form a continuous 35 worm or spiral for the total length of the barking drum. The pitch of the spiral bark removing members is so arranged as to positively and steadily move or feed the logs, 40 blocks or sticks of wood toward the outlet end of the drum at such speed as will remove all of the bark without bruising and slivering their ends or surfaces. The drum is also of sufficient diameter, so that logs, 45 blocks or sticks of wood of any size used for producing wood pulp will receive a tumbling action, causing the bark to be removed by the spiral bark removing elements in the drum. The water in the receiving section of 50 the barking drum is used to moisten the wood placed therein, so that the bark can be more readily detached by the spiral bark removing members. The wood which is placed in the receiving section is transmitted by the spiral barking elements from said section into the next succeeding section disposed adjacent thereto over the inner bulk 55 head, owing to the combined tumbling action, and the feeding effect produced by the spiral members, also by floating in the soaking liquid. As the wood advances through the drum due to the combined tumbling action and feeding effect produced by the spiral barking members, the pieces of broken bark removed from the wood by the bark 60 knockers are broken into small pieces by the tumbling action of the material and these small pieces drop through the spaces between

the slats or bars 15 and are caught upon the conveyer D below and by said conveyer, said pieces are carried away from the machine. It is not necessary to secure the drum sections together, although the drawing illustrates the pairs of adjacent end rings such as 4 and 6 fastened together by bolts 32. 70

When desired the sections of the drum when not secured together can be driven at different speeds by using sprocket pinions 29 of smaller or larger diameter. When using pinions successively increasing in diameter toward the delivery end of the drum the wood is carried at increasing speed toward 75 said delivery end. 80

The machine as described cleans the wood entirely of bark leaving the wood in prime condition for producing the pulp or chips free from bark and splinters. Water can be poured upon the slatted portion of the drum 85 for cleaning purposes when desired.

In accordance with the patent statutes, I have described the principles of operation of my invention, together with the apparatus which I now consider to represent the best 90 embodiment thereof, but I desire to have it understood that the construction shown is only illustrative, and that the invention can be carried out by other means and applied to uses other than those above set forth within 95 the scope of the following claims.

Having described my invention, what I claim as new and desire to protect by Letters Patent is:

1. A barking drum, comprising, in combination, a rotatable slatted drum having a wood receiving end, means for revolving said drum, and means arranged within said drum for loosening the bark on the wood and positively advancing the wood through 100 the drum from its receiving end to its opposite end.

2. A barking machine, comprising, in combination, a rotatable drum through one end of which the wood to be barked is introduced, means for revolving said drum, and a bark knocker spirally arranged on the inner surface of said drum to advance the wood through the drum and against which the wood is adapted to impinge to loosen and 110 remove the bark. 115

3. A barking drum, comprising, in combination, a rotatable slatted drum having a wood receiving end, means for revolving said drum, and a plurality of spaced devices 120 arranged on the inner surface of said drum to positively advance the wood through the drum and against which the wood is adapted to impinge to loosen and remove the bark.

4. A barking drum, comprising, in combination, a rotatable slatted drum having a wood receiving end, means for revolving said drum, and a plurality of spaced devices spirally arranged on the inner surface of 125 said drum to positively advance the wood 130

through the drum and against which the wood is adapted to impinge to loosen and remove the bark.

5. A barking machine, comprising, in combination, a rotatable drum having a plurality of longitudinal sections arranged endwise together, a set of bark knockers spirally arranged on the inner surfaces of said sections, said knockers being placed endwise together to form substantially continuous wood feed-

ing spirals traversing the entire length of said drum and for positively advancing the wood therethrough, one of said sections being formed with a soaking compartment for the wood, and the remainder of said sections having passages through which the free bark may pass.

In testimony whereof, I have signed my name to this specification.

JOHN J. ROSS.
